Primary Examiner — Elizabeth Albert*(74) Attorney, Agent, or Firm* — The Marbury Law Group, PLLC(57) **CLAIM**

The ornamental design for a correction tool, as shown and described.

DESCRIPTION

FIG. 1 is a left side view of the correction tool showing our new design;

FIG. 2 is a right side view thereof;

FIG. 3 is a top plan view thereof;

FIG. 4 is a bottom plan view thereof;

FIG. 5 is a front view thereof;

FIG. 6 is a rear view thereof; and,

FIG. 7 is a top left side perspective view thereof.

1 Claim, 7 Drawing Sheets---
